(57) **CLAIM**

The ornamental design for an optical cover with faceted surface, as shown and described.

DESCRIPTION

FIG. 1 is an isometric view, as seen from a first angle, of an optical cover with faceted surface;

FIG. 2 is an isometric view, as seen from a second angle, of the optical cover with faceted surface of FIG. 1;

FIG. 3 is an end elevation of the optical cover with faceted surface of FIG. 1, an opposing end elevation thereof being identical;

FIG. 4 is a front elevation of the optical cover with faceted surface of FIG. 1, a rear elevation thereof being identical; FIG. 5 is a cross-sectional view of the optical cover with faceted surface of FIG. 1, taken at cross-sectional plane 5-5' indicated in FIG. 4;

FIG. 6 is a top plan view of the optical cover with faceted surface of FIG. 1; and,

FIG. 7 is a bottom plan view of the optical cover with faceted surface of FIG. 1.

Bold broken lines indicate the bounds of the claim. Light weight broken lines illustrate portions of the optical cover with faceted surface; all broken lines form no part of the claimed design.
